CLAIM

The ornamental design of a laundry sorter, as shown and described.

DESCRIPTION

FIG. 1 is a perspective view of the laundry sorter of the present invention;

FIG. 2 is a front elevational view, the rear elevational view being a mirror image thereof;

FIG. 3 is a left side elevational view with a right side elevational view being a mirror image thereof;

FIG. 4 is a top plan view thereof; and,

FIG. 5 is a bottom plan view thereof.

The broken line showing of bags is for illustrative purposes only and forms no part of the claimed design.
